UNITED STATES PATENT OFFICE.

WILLIAM D. HOXIE, OF BROOKLYN, NEW YORK, ASSIGNOR TO THE BABCOCK & WILCOX COMPANY, OF BAYONNE, NEW JERSEY, A CORPORATION OF NEW JERSEY.

WATER-TUBE BOILER.

1,215,806.

Specification of Letters Patent. Patented Feb. 13, 1917.

Application filed March 23, 1914. Serial No. 826,546.

To all whom it may concern:

Be it known that I, WILLIAM D. HOXIE, a citizen of the United States, residing in New York city, borough of Brooklyn, county of Kings, and State of New York, have invented certain new and useful Improvements in Water-Tube Boilers, of which the following is a specification.

My invention relates more particularly 10 to improvements in sectional or water tube boilers and although not limited to a marine boiler its primary utility will be in marine work. In its main features the present boiler comprises a bank of generating 15 tubes inclined upward from the front to the rear so that the combustion space within the furnace is lowest at the front and highest at the rear portion. Such form of combustion chamber enables combustion to be 20 completed before the gases come into contact with the heating surfaces.

Another feature of the invention is the 25 employment of a special form of tube by which I am enabled to increase the ratio of generating surface to the combustion area, thereby improving the economy, and in connection therewith the employment of downcomers of greater diameter than the generating tubes and embedded in the side walls 30 of the setting on both sides of the generating tubes. These and other features of the invention will be understood by reference to the accompanying drawings in which Figure 1 is a longitudinal section of one embodiment of my invention; Fig. 2 a transverse section; Fig. 3 a side elevation of the downcomers; and Fig. 4 a longitudinal section of a part of a boiler showing a modification. Similar reference numerals indicate similar parts in the several views.

Referring to the drawings the numeral 1 45 designates a cylindrical steam drum made of one shell sheet and one tube sheet, the sheets being butt-jointed and secured with double butt straps. The water drum 2 is made of one shell sheet and a flanged tube sheet with the longitudinal seams lapped, the tube sheet being flanged to form the outside lap.

50 The steam and water drums are connected by a bank of generating tubes 3 containing sufficient generating surface for the particular boiler required. In the drawings I have shown nineteen horizontal rows, all the tubes 55 of which are curved at both ends and are

straight for the rest of their length, and enter the drums radially. The degree of curvature of the lowermost tubes at their upper ends is substantially the same as that of the uppermost tubes at their lower ends. 60 By curving the generating tubes in the manner described I am enabled to increase the ratio of generating surface to combustion area. Also, as shown, tubes at the lower part of the bank have their lower ends 65 curved upwardly and those at the upper part of the bank have their ends curved downwardly, and some of the tubes of the intermediate rows have reversely curved ends. 70

Also expanded into the drums on both sides of the generating tubes are downcomers 4 (see Fig. 3) of greater diameter than the generating tubes, curved at both ends and straight for the rest of their length, except 75 the next to the bottom row, the tubes of the latter being curved at their upper ends only.

The parts above described are supported above a combustion chamber 5, the walls being built of fire brick, between which and 80 the casing is a lining of asbestos felt 6. As shown in Fig. 2 the downcomers 4 are located between the brick lining and the outer casing in the upper part of the setting, and are embedded in the asbestos lining to insulate them as much as possible from the furnace heat. 85

To direct the gases to the uptake end of the tubes, and across the tubes, I employ a baffle 7 supported on the next to the bottom row of tubes, said baffle extending from the water drum toward the steam drum about two-thirds the length of the tubes, and terminating short of the curved section of the lowermost tubes. Supported 90 upon the upper row of tubes, as shown in Fig. 1, is a second longitudinal baffle 8 extending from the steam drum about two-thirds the length of the tubes and terminating short of the curved section of the uppermost tubes and which baffle also forms the roof of the combustion chamber. From the ends of baffles 7 and 8 cross baffles 9 and 10, respectively, extend about half-way across the bank of tubes, thus dividing the bank 100 into three transverse passes beginning at the uptake end of the tubes. The course of the gases is indicated by the arrows, the gases finally escaping through a vertical uptake 11. As shown, the baffles 9 and 10 are 105

in planes at right angles to the general axis of the bank of tubes, and across the tubes at the straight sections thereof. The longitudinal baffle 8 may be made in several sections widthwise of the boiler, as shown in Fig. 2, and these sections may be hinged, as at 12, to enable them to be turned back to give access to the tubes for cleaning.

The space between the second and third rows of tubes from the bottom is greater than that between the other rows to provide a soot collecting space, the soot being removed through cleaning doors 13.

If oil fired, any suitable oil burner or mechanical atomizer 14 may be employed. It is located, as shown in Fig. 1, to inject the fuel spray into the lower end of the combustion chamber, said chamber increasing in size in the direction of the entering fuel. As the chamber 5 increases in height from the front to the rear, ample space is provided for the combustion of the mixture of atomized oil and air, and a travel of sufficient length to insure that the combustion shall be completed before the gases reach the generating surfaces. Furthermore the large area of heated brick work radiates heat to assist in the combustion. By this arrangement a high furnace temperature is established.

Fig. 4 shows an arrangement for a superheater boiler. In this form the baffle 15 extends from drum 1 to the stack outlet 11 above the bank of tubes to provide space sufficient to accommodate a superheater 16 above the first and second passes. The inner wall of the flue outlet serves as an upward extension of cross baffle 10.

What I claim and desire to secure by Letters Patent of the United States is:—

1. A steam boiler of the class described having a bank of inclined tubes, drums into which said tubes are expanded, said tubes being curved at both ends and straight for the rest of their length and entering the drums radially, and downcomers at the side of the bank and expanded into said drums.

2. A steam boiler of the class described having a bank of inclined tubes, drums into which said tubes are expanded, said tubes being curved at both ends and straight for the rest of their length and entering the drums radially, downcomers at the side of the bank and expanded into said drums, a longitudinal baffle to direct the gases to the uptake ends of the tubes, and cross baffles across the straight portions of the tubes.

3. A steam boiler of the class described having a bank of inclined tubes, drums into which said tubes are expanded, said tubes being curved at both ends and straight for the rest of their length and entering the drums radially, downcomers at the side of the bank

and expanded into said drums, longitudinal baffles extending from said drums, and transverse baffles from the ends of the longitudinal baffles extending across the straight portions of the tubes.

4. A steam boiler of the class described, comprising a transverse mud drum at the front of the setting and above the inlet for fuel, an elevated transverse steam and water drum at the rear of the setting, a bank of rearwardly and upwardly inclined water tubes expanded into the drums and connecting them, said tubes being curved at both ends and straight for the major portion of their length and entering the drums on substantially radial lines, a combustion chamber extending beneath the major portion of the length of the tubes, a horizontal baffle extending rearwardly and upwardly from the mud drum and giving a combustion chamber which enlarges rearwardly, transverse baffles arranged to give the gases up passes and down passes and an offtake flue over the mud drum and leading from the last up pass of the gases.

5. A steam boiler of the class described having a bank of inclined tubes, drums into which said tubes are expanded, said tubes being curved at both ends and straight for the rest of their length and entering the drums radially, and downcomers located in the side walls of the setting and expanded into said drums having the same general inclination to the horizontal as the generating tubes.

6. In a steam boiler of the class described, the combination of a bank of inclined generating tubes, drums into which the tubes are expanded, baffles extending from said drums, cross baffles from the ends of the first-named baffles, and downcomers on each side of the bank of tubes and expanded into said drums.

7. A steam boiler of the class described having a bank of tubes inclined upward from the front of the setting to provide a combustion space increasing in size toward the rear, drums into which said tubes are expanded, baffles extending from said drums, cross baffles from the ends of the first-named baffles, a superheater in the space between the tubes and the baffle extending from the steam drum, and downcomers on each side of the bank of tubes and expanded into said drums.

In testimony whereof I have hereunto signed my name in the presence of two subscribing witnesses.

WILLIAM D. HOXIE.
